DUPLICATING MACHINE

John E. Euth, Chicago, Ill., assignor to United
Autographic Register Co., a corporation of
Illinois

Application December 18, 1933, Serial No. 703,014

10 Claims. (Cl. 197—133)

This invention relates particularly to duplicating machines adapted to the purpose of filling in forms on continuous-form stationery, and to improved means for manipulating the stationery 5 in the machine.

The primary object of the invention is to provide a simple, easily operable device for alining stationery strips in writing position on the platen, and a tensioning device for tensioning each strip, 10 individually, in writing position.

A further object of the invention is to provide an alining and tensioning device which may be swung upwardly into a position which will facilitate threading of the stationery strips from 15 a suitable source of supply, through the tensioning device to the front of the machine. The invention is illustrated in a preferred embodiment in the accompanying drawings, in which—

Figure 1 is a side elevational view of a machine 20 embodying the invention, the loading position of the tensioning device being indicated by dotted lines; Fig. 2, a broken plan view of the same, with the typewriter removed; Fig. 3, a broken longitudinal sectional view, taken as indicated at line 3 of Fig. 2; Fig. 4, a side elevational view 25 of the upper frame of the tensioning device, taken as indicated at line 4 of Fig. 5; and Fig. 5, a sectional view taken as indicated at line 5—5 of Fig. 3.

30 In the embodiment illustrated, A designates a main frame comprising standards A' having a surmounting bed A², in which is mounted a platen A³; B, a typewriter machine movably mounted on the bed A²; C, a carbon supply 35 device carried by the bed of the machine; D, a clamping device operating in front of the platen A³; E, an alining and tensioning device mounted between the arms of the bed A²; and F, multiple-strip stationery supported beneath the alining and tensioning device E.

35 The frame A is of known construction having standards A' connected by cross-rods 10 which are held by nuts 10^a. The bed A² is fixedly mounted on the standards and comprises arms 40 connected at the rear by cross-rod 11, held by nuts 11^a, and at the front with a cross-bar 12.

45 Like the frame, the platen A³ is standard equipment and is mounted in the manner usual to this type of machine. Such a mounting is described in my co-pending application, Serial Number 677,127 filed June 22, 1933. The mechanism is ordinarily used to depress the writing platen but for the purpose of the present invention, this action is not necessary and the mechanism is used merely to raise the clamping device 50

D. We might say that the lever arm 13 of the platen lowering mechanism is connected to a rod 20 which may be drawn downwardly by means of a treadle 21 which is pivoted at 22 to a fixed arm 23 on the cross-rod 10. The treadle mechanism serves also to release the tensioning device E as will be explained below. 5

The typewriting machine B may be of any well known construction. It is capable of transverse movement in the operation of printing 10 words, characters, etc. and is movable longitudinally on racks 24 provided on the arms of the frame A².

The carbon-supply device C comprises a multiple-strip carbon-supply roll 25 and a take-up 15 roll 26 mounted on opposite sides of the platen in brackets 27, and is adapted to supply continuous-carbon strips across the platen. The clamping device D comprises a tear-off bar 28 which is pivotally mounted on the frame A² and actuated by the platen mechanism as described 20 in my co-pending application mentioned above. A pair of paper guides 30 are also attached to the cross-bar 12 in front of the clamping member and help to guide the stationery, when the same is being advanced over the platen. If desired, the cross-bar may be provided with register pins 31 adapted to engage perforations provided in the stationery. When register pins are provided, the clamping bar 28 may be perforated 30 as indicated at 32 to permit the clamping bar to press the stationery down around the register pins.

The alining and tensioning device E comprises an auxiliary frame which is adapted to rest upon 35 the rear cross-rod 11 and upon a pair of studs 34 provided in the bed A², in the rear of the platen.

40 As best shown in Figs. 3—5 the auxiliary frame comprises a stationary base frame 35 and an upper frame 36 pivotally connected at 37 to an upwardly extending ear 38 of the base frame. The base frame comprises a pair of L-shaped side members 39 whose rear ends are connected by an angle member 40 and whose front ends are rigidly connected to a channel member 41. As shown 45 in Fig. 3, the rear portion of the side members is cut away to permit the members to fit down over the cross-bar 11. If desired, the base frame 35 may be fixed to the frame A² by means of 50 screws 39^a.

55 The upper frame 36 comprises a pair of channel members 42 which are connected at their rear ends by a Z-shaped angle member 43 which also fits down and rests upon the cross-bar 11. The 55

channel members are provided with a continuous longitudinal slot 44 in which is journaled a series of tensioning members or rollers 45. Springs 45^a are connected at one end to the channel members 42 and at the other end to the end portions of the rollers 45 by means of yokes 45^b. As shown in Figs. 4 and 5, the inner portions of the channel members are provided with slides 46 which are held in position by fingers 47 struck 5 from the channel members. Each of the slides is provided with upwardly projecting fingers 48 which are adapted to engage the tensioning members 45 and limit their rearward movement. For the purpose of illustration, the upper portions of the fingers 48 are shown connected together so that in effect each of the tensioning members extends through slots 44 in the channel members 42 and also through a pair of individual slots provided in the slides 46. A cross bar 49 extends through slots 50 in the channel members and serves to draw the slide members forwardly. The cross member is actuated by means of a chain 51 which has one end adjustably connected to a bracket 52, depending from 10 the channel member 41, by means of a thumb screw 53. A crank member 54 is pivotally mounted on the bracket at 55, so that when its front end is depressed by the lever arm 13, a roller 56 at its rear will engage a loop in the chain and thereby cause the cross member to draw the 15 slides and rollers forwardly.

The base frame is provided with a rigidly connected cross member 60 over which all of the stationary strips F are led. A rock member 62 is journaled in the upper frame and is provided with a finger member 63, adjustably held by a screw 63^a, which is adapted to press the strips against the cross member 60. A torsion spring 64 urges the finger member into gripping position. The outer ends of the rock member are squared at 65 and are provided with actuating arms 66 which are engaged by studs 67 on the slide members 46 so that when the slide members are drawn forwardly, the finger member 63 will be rocked from gripping position.

The stationery F comprises a plurality of strips of slips 70 which are provided with register-perforations 71, and are connected end to end at lines of weakening 72. The stationery may be 50 zig-zag folded or in the form of a plural wound roll as shown in Fig. 1. When a roll is used, the stationery is usually wound on a hollow cardboard core which is impaled by a shaft 13 which is removably mounted in arms 74 depending 55 downwardly from the aligning and tensioning device E.

To load the machine, the upper frame 36 is swung to the position indicated by dotted lines in Fig. 1. This movement will raise the finger member 63 from contact with the cross member 60 and will permit all of the stationery strips to be threaded over said cross member and around the rollers 45, individually, as indicated in Fig. 3. The upper frame may then be lowered into its normal position and the operator may raise the clamping bar 28 and draw the rollers 45 forwardly by depressing the treadle 21. The stationery strips are then led over the platen in interleaved relation with the carbon and the 65 register perforations engaged by register pins 31. Upon release of the treadle, the clamping bar 28 will be lowered into gripping position. The finger member 63 will grip all of the strips against the cross member 60 and each of the 70 tensioning rollers 45 will be permitted to move

rearwardly under the influence of springs 45^a. Thus, it will be seen that each of the strips will be drawn back into alignment and tensioned slightly so as to lie flat on the platen.

The foregoing detailed description is given for 5 clearness of understanding only and no unnecessary limitations should be understood therefrom, but the appended claims construed as broadly as permissible, in view of the prior art.

What I regard as new and desire to secure by 10 Letters Patent is:

1. In a duplicating machine: a frame having a platen over which stationery strips may be led from the rear; means for fastening the front end portion of the strips in front of said platen; and a tensioning device in rear of said platen, comprising means for simultaneously gripping all of the strips together to prevent advancement thereof, tensioning members mounted so as to engage each strip individually in advance of the gripping means and to draw the same taut over the platen, and means for releasing said tensioning members and gripping means from operative engagement with the strips.

2. In a duplicating machine: a frame having 25 a platen over which stationery strips may be led from the rear; means for fastening the front end portion of the strips in front of said platen; a tensioning and aligning device in rear of said platen comprising holding means for simultaneously 30 holding all of the strips together to prevent advancement thereof, tensioning members forming a separate loop in each strip in rear of the platen, springs connected to each of said tensioning members so as to urge the same rearwardly to tension 35 said strips, and movable means adapted to free the strips from the action of said tensioning members and holding means.

3. In a duplicating machine: a frame having a platen over which stationery strips may be led 40 from the rear; means for fastening the front end portion of the strips in front of said platen; and a tensioning device in rear of said platen comprising a cross bar over which all of the strips may be led, a gripping member adapted to grip 45 all of the strips against said bar, a series of spring held movably mounted tensioning bars each engaging an individual loop formed in each of said strips so as to tension the same over the platen, and slide-members for drawing the tensioning bars forwardly, said slide-members engaging and 50 releasing said gripping member when moved forwardly.

4. In a duplicating machine: a frame having a platen over which stationery strips may be led 55 from the rear; a clamping bar pivotally mounted on the front of said frame and adapted to clamp the front end portion of the strips; a tensioning device in rear of said platen comprising a cross bar over which all of the strips may be led, a 60 gripping member adapted to grip all of said strips against said bar, a series of spring held movably mounted tensioning bars each engaging an individual loop formed in each of said strips so as to tension the same over the platen, and slide-members 65 for drawing the tensioning bars forwardly, said slide-members engaging and releasing the gripping member in their forward movement; and treadle means connected to said clamping bar and the slide-members so as to simultaneously 70 release the clamping bar and draw the slide-members forwardly.

5. In a duplicating machine: a frame having 75 arms extending rearwardly; a platen mounted in the front portion of said frame over which sta-

133

2,047,678

3

tionery strips may be drawn from the rear; clamping means for gripping said strips in front of the platen; an auxiliary frame mounted in said arms in rear of the platen, said auxiliary frame comprising a base frame and an upper frame pivotally mounted thereon; a gripping device mounted in said upper frame and adapted to co-operate with the lower frame in gripping all of said strips together; and individual tensioning 5 rolls slidably mounted in said upper frame so as to form loops in strips threaded between the clamping means and the gripping device.

6. A tensioning device adapted for use in connection with a flat bed platen having means for gripping the ends of strips led thereover, comprising: a pair of parallel side members each provided with a longitudinal slot; a series of rollers journaled in said slots, each roller being provided with a pair of springs connected to said side members so as to urge the rollers rearwardly; a pair of slides slidably mounted in the side members and having fingers adapted to engage the rollers; means for drawing the slides forwardly; and gripping-means adapted to yieldingly grip together a 15 plurality of said strips threaded therethrough and around the rollers.

7. Mechanism as specified in claim 6, in which the gripping-means comprises a fixed cross-bar, a rock shaft having a finger adapted to engage said cross-bar, said rock shaft having an arm adapted to be engaged by one of the slides and actuated thereby.

8. In a duplicating machine: a frame having a platen over which stationery strips may be led from the rear; clamping means for fastening the front end portion of the strips in front of said platen; a tensioning device in rear of said platen comprising releasable means for gripping all of the strips to prevent forward advancement there-

of, means for engaging each strip individually between the clamping means and the gripping means to draw the strips taut over the platen; and a unitary mechanism for relieving the tension on each strip and releasing the gripping means. 5

9. In a duplicating machine: a frame having a platen over which stationery strips may be led from the rear; clamping means for fastening the front end portion of the strips in front of said platen; a tensioning device in rear of said platen 10 comprising releasable means for gripping all of the strips to prevent forward advancement thereof, means for engaging each strip individually between the clamping means and the gripping means to draw the strips taut over the platen; 15 and treadle mechanism for relieving the tension on each strip and releasing the gripping means and the clamping means.

10. A tensioning device adapted for use in connection with a flat bed platen having means for gripping the ends of strips led thereover, comprising: a pair of parallel side members each provided with a longitudinal slot; a series of rollers journaled in said slots, each roller being provided with a pair of springs connected to said side members so as to urge the rollers rearwardly; a pair of slides slidably mounted in the side members and having fingers adapted to engage the rollers; means for drawing the slides forwardly; and gripping-means comprising a fixed cross-bar 30 over which said strips may be led, a rock shaft provided with a clamping arm adapted to press the strips against said cross-bar and an actuating arm adapted to be engaged by one of the slides to rock said clamping arm from engagement with 35 the strips, and a spring urging said rock shaft to clamping position.

JOHN E. EUTH.
